CLAIM

The ornamental design for a garment bag, substantially as shown and described.

DESCRIPTION

FIG. 1 is a front elevational view of a garment bag showing our new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof; and

FIG. 7 is a front perspective view of the garment bag shown in FIG. 1, in a folded condition, with a flap in a raised condition, and with a carrying strap attached to the bag.

FIG. 2

FIG. 3
